DESIGN FOR A GATE

Paul L. Bult, Chicago, Ill.

Application November 5, 1945, Serial No. 123,457

Term of patent 14 years

(Cl. D28—1)

To all whom it may concern:

Be it known that I, Paul L. Bult, a citizen of the United States, residing at Chicago, in the county of Cook and State of Illinois, have invented a new, original, and ornamental Design for a Gate, of which the following is a specification, reference being had to the accompanying drawing, forming a part thereof, in which:

Figure 1 is a front elevation of a gate show-

ing my new design; and Fig. 2 is a top plan view of the gate.

The dominant features of my design reside in the portions shown in full lines.

I claim:

The ornamental design for a gate, as shown and described.

PAUL L. BULT.
